UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

AIR-FEED LOCK FOR ROCK DRILLS.

Application filed June 16, 1922. Serial No. 568,831.

To all whom it may concern:

Be it known that I, FRED M. SLATER, a citizen of the United States, and a resident of Easton, in the county of Northampton and State of Pennsylvania, have invented a certain Air-Feed Lock for Rock Drills, of which the following is a specification, accompanied by drawings.

This invention relates to fluid actuated rock drills but more particularly to a device for controlling the feeding element of a stope drill, although the invention may be applied to any drill having a fluid actuated feeding element.

The objects of the invention are to enable the members of the fluid actuated feeding element of a stope drill for instance, to be positively locked against relative movement when desired, and effect the control of the locking device preferably by fluid actuated means under the manual control of the operator.

Another object of the invention is to enable the members of the feeding elements to be locked automatically and prevent feeding, by devices adapted to be brought into operation by a sudden substantially unrestrained forward feeding movement of one of the feeding element members and the drill cylinder. In case the drill steel breaks for instance, or for some other reason well understood, the feeding element may suddenly force the machine forward and unless such sudden jump is restrained, practically instantly, the operator or other drill runners may be injured or the machine damaged.

To these and other ends, which will hereafter appear, the invention consists of the combinations of elements and arrangements of parts substantially as described and claimed in this specification and shown in its preferred form in the accompanying drawings, in which—

Figure 1 is a side elevation partly in longitudinal section, of so much of a stope drill as will serve to illustrate the invention.

Figure 2 is an enlarged detail vertical sectional elevation of the feeding element.

Figure 3 is an enlarged detail vertical sectional elevation partly broken away of a modification of the feeding element, and

Figure 4 is a view similar to Figure 3 with the parts in a different position.

Referring to the drawings, the cylinder A of a stope drill is provided with the front head B, through which the drill steel C extends in the usual manner, in order to receive the blows of impact of a hammer piston. The cylinder is also provided with a cylinder back extension D, and had a head block E, which contains the throttle valve F having the handle G controlling the supply of motive fluid from the inlet J to the cylinder and to the air feeding element. The head block E is mounted on the feed cylinder K which is formed with the feed cylinder flange L. The parts so far described are adapted to be secured together by the usual side bolts (not shown).

In the form of fluid actuated feeding element illustrated, the feed cylinder K forms one of the two relatively movable members, and is connected to the cylinder A and its associated parts while the feed piston O and piston rod P forming the other feeding element member, are stationary and provided with the rock engaging pointer Q. In accordance with this invention, a rack R is provided on one of the members as for instance, the stationary piston rod P and a worm S is mounted to move with the other movable member and engages the rack R. The worm S is free to rotate as the feeding elements move relatively to each other until mechanism is brought into operation for holding or locking the worm so that it cannot turn and thus lock the feeding mechanism.

The rack R may be secured to the piston rod P as by means of the screws T, and the worm S is rotatable but longitudinally slideable in a housing U carried by a housing support V suitably connected to the head block E as by means of a screw threaded connection W and the lock nut X, so that the housing U moves with the cylinder A and feed cylinder K.

The gear housing U is provided with the stud or worm support Y having a conical bearing Z forming a clutch member for the worm S, which in turn has an internal clutch surface and is loosely mounted on said stud. A rod a extends through the worm housing support V and is held in retracted position by means of a coiled spring b bearing on the housing U at the lower end and abutting a shoulder c on the rod a at the upper end.

end. The rod *a* is adapted to be brought into contact with a head or button *d* mounted in the housing, which may be pressed against the worm *S* in order to force said worm tightly to its conical or tapered bearing *Z* on the stud *Y*, with sufficient frictional contact between the clutch surfaces of the worm and its bearing to prevent said worm from turning. The upper end of the rod *a* bears against a plunger or head *e* over which is arranged a diaphragm *f* of rubber, calf skin, metal or other suitable material suitably secured within a chamber in the head block by means of the screws *g*. A spring *h* beneath the head or plunger *e* normally tends to expand the diaphragm *f* and maintain it in the position indicated in Figure 1. When fluid pressure is admitted to the diaphragm chamber, with the throttle valve *F* in the position indicated in Figure 2, the diaphragm will be depressed, thus depressing the head or plunger *e* and the rod *a*, which in turn presses the head or button *d* against the worm *S* and forces said worm tightly upon the tapered or conical bearing forming a clutch member on the stud *Y*. The tendency of the said cylinder *K* to move, due to the admission of pressure above the piston *O* is then resisted by the inability of the worm *S* to turn on its bearing, owing to the frictional contact between the worm and its conical bearing. The parts will be effectually locked and feeding will be prevented.

Owing to the construction shown, the operation of the locking device is automatic under certain conditions and will prevent sudden jumping or feeding forward of the rock drill in case, for instance, the drill steel should break or for other well understood causes. If for instance the machine should suddenly start to jump forward, the quick feeding movement will carry the housing *U* suddenly forward and will drive the clutch member of the tapered stud *Y* into its clutch seat in the worm *S* and thus lock said worm from turning, which will prevent the feeding elements from having relative movement. This is an important and desired feature as well understood by those skilled in the art.

In the modification shown in Figures 3 and 4, the worm *S* is slidably but relatively mounted on the sleeve *j* carried by the head *k* held within the lower end of the housing *U*. A coiled spring *o* within the sleeve *j* provided with a button *p* normally holds the worm *S* away from the head *k*. Both the worm *S* and the head *k* are provided with cooperating clutch surfaces preferably in the form of serrated or toothed surfaces or elements *q* and *r*, and when the rod *a* is forced downwardly against the tension of the spring *b*, the worm *S* will be forced downwardly until the clutch surfaces or

elements *q* and *r* are brought into engagement, thus locking the worm from turning, and locking the feeding elements. The form of device shown in Figures 3 and 4 also operates satisfactorily and well, except that it is not intended to have the function of automatic operation which is present in the form of device shown in Figures 1 and 2, because in Figures 1 and 2 the sudden upward movement of the worm housing *U* will tend to force the tapered bearing into the worm *S* and produce increased frictional engagement with the worm, even with a slight upward movement of the housing, while in Figures 3 and 4, the housing *U* must move upwardly a sufficient distance to engage the teeth of the clutch elements *q* and *r* before the worm *S* can be locked. It is conceivable that under some circumstances the devices shown in Figures 3 and 4 may operate automatically in case, for instance, there is a sufficient substantially instantaneous upward travel of the housing *U* to effect engagement between the clutch elements *q* and *r*.

I claim:

1. In a fluid actuated rock drill, the combination of a cylinder, a fluid actuated feeding element having relatively movable members, one being connected to said cylinder, and the other being stationary, a rack on one of said members, a worm carried by the other member engaging said rack, clutch elements both carried by the said movable member of the feeding element for locking said worm against rotation, and means acting directly on the worm for moving the clutch elements to operative position.

2. In a fluid actuated rock drill, the combination of a cylinder, a fluid actuated feeding element having relatively movable members, one being connected to said cylinder, and the other being stationary, a rack on one of said members, a worm carried by the other member engaging said rack and fluid actuated means acting directly on the worm for holding said worm against rotation.

3. In a fluid actuated rock drill, the combination of a cylinder, a fluid actuated feeding element having relatively movable members, one being connected to said cylinder, and the other being stationary, a rack on one of said members, a tapered stud carried by the other member, a worm mounted thereon engaging said rack and means for frictionally holding said worm against rotation on said stud.

4. In a fluid actuated rock drill, the combination of a cylinder, a fluid actuated feeding element having relatively movable members, one being connected to said cylinder, and the other being stationary, a rack on one of said members, a stud carried by the other member, a longitudinally slidab

worm rotatable about said stud and engaging said rack and means for holding said worm against rotation on said stud.

5. In a fluid actuated rock drill, the combination of a cylinder, a fluid actuated feeding element having relatively movable members, one being connected to said cylinder,

5 10 and the other being stationary, a rack on one of said members, a slideable worm carried by the other member engaging said rack, and frictional means acting directly on the worm for holding the said worm against rotation.

6. In a fluid actuated rock drill, the combination of a cylinder, a fluid actuated feeding element having relatively movable members, one being connected to said cylinder, and the other being stationary, a rack on one of said members, a worm carried by the other member engaging said rack, a frictional clutch surface on the worm, a cooperating frictional clutch element carried by the said movable member of the feeding element for locking said worm against rotation, and 25 fluid actuated means acting directly on the worm for moving the clutch elements to operative position.

7. In a fluid actuated rock drill, the combination of a cylinder, a fluid actuated feeding element having relatively movable members, one being connected to said cylinder, and the other being stationary, a rack on one of said members, a worm carried by the other member engaging said rack and means

for automatically locking said worm against 35 rotation adapted to be brought into operation by a sudden substantially unrestrained forward feeding movement of the movable feeding element, said means including a stud having a tapered bearing in said worm. 40

8. In a fluid actuated rock drill, the combination of a cylinder, a fluid actuated feeding element having relatively movable members, one being connected to said cylinder, and the other being stationary, a rack 45 on one of said members, a worm engaging said rack and carried by the other member, a tapered stud having a bearing in said worm, and fluid actuated means for locking said worm against rotation. 50

9. In a fluid actuated rock drill, the combination of a cylinder, a fluid actuated feeding element having relatively movable members, one being connected to said cylinder and the other being stationary, means for 55 admitting pressure fluid to actuate said members, a rack on one of said members, a toothed member meshing with said rack and having limited movement in the other member, a tapered stud having a bearing in said 60 toothed member adapted to automatically hold the toothed member against rotation, and brought into operation by a sudden substantially unrestrained forward feeding movement of the movable feeding element. 65

In testimony whereof I have signed this specification.

FRED M. SLATER.
